FIG. 3

INVENTOR,
WILLIAM H. ZIMMERMAN

BY

Wm H. Zimmerman

AGENT

UNITED STATES PATENT OFFICE

2,583,622

BRUSH FOR PHONOGRAPH NEEDLES

William H. Zimmerman, San Diego, Calif.

Application April 5, 1947, Serial No. 739,639

6 Claims. (Cl. 274—38)

1

My invention relates to a brush for phonograph needles and the objects of my invention are:

First, to provide a brush combination with long lasting needles such as sapphire point needles for removing abrasive material from records being played by the needles greatly increasing the life of the records and reception therefrom conducted by the needle traversing the same;

Second, to provide a brush for phonograph needles of this class which is constantly resiliently loaded providing slight constant pressure of the brush on the record following the needle and overlapping the path thereof so that successive track spirals are pre-cleaned before the needle comes in contact therewith;

Third, to provide a brush for phonograph needles of this class pivoted directly to the phonograph needle and properly insulated therefrom whereby simplicity of installation and improved reception is accomplished;

Fourth, to provide a phonograph needle brush of this class which is very simple and easy to install;

Fifth, to provide a brush of this class which is substantially automatic in its operation after it is installed;

Sixth, to provide a brush of this class which automatically compensates for wear of the bristles thereof; and

Seventh, to provide a brush for phonograph needles of this class which is very simple and economical of construction, efficient in operation and which will not readily deteriorate or get out of order.

With these and other objects in view, as will appear hereinafter, my invention consists of certain novel features of construction, combination and arrangement of parts and portions as will be hereinafter described in detail and particularly set forth in the appended claims, reference being had to the accompanying drawing and to the characters of reference thereon forming a part of this application in which:

Figure 1 is a side elevational view of my brush for phonograph needles shown in connection with a conventional phonograph needle; Fig. 2 is a bottom plan sectional view taken from the line 2—2 of Fig. 1 showing portions further broken away and in section to amplify the illustration; and Fig. 3 is a sectional view taken from the line 3—3 of Fig. 1.

Similar characters of reference refer to similar parts and portions throughout the several views of the drawing.

The needle 1, clip 2, spring 3, brush holder 4

2

and brush 5 constitute the principal parts and portions of my brush for phonograph needles.

The needle 1 is a substantially conventional long life needle having a sapphire point or other long wearing point 1a adapted to engage conventional phonograph records. This needle 1 is provided with an annular groove 1b therein arranged to receive the clip 2 which is substantially U-shaped as shown in Fig. 3 of the drawing. Engaging this clip 2 at its lower side is one end of the spring 3. This spring 3 is a coiled spring surrounding the shank portion 1c of the needle 1 and the lower end of said spring 3 engages the upper side of the brush holder 4, tending to force the same downwardly to the point 1a of the needle 1. This brush holder 4 is provided with a surrounding strap portion 4a within which the electrical insulation 4b surrounds the bristles 5a of the brush 5, and this brush holder 4 is also provided with a bore portion 4c therein slideable over the outside of the needle 1 at its shank portion 1c. A shoulder 1d is provided on the needle 1 for retaining the brush holder 4 thereon against compression of the spring 3.

25 The operation of my brush for phonograph needles is substantially as follows:

The record, as indicated by dash lines A is engaged by the point 1a of the needle 1. The upper end of the needle 1 is secured in connection with a conventional phonograph pick-up head, or the like, and the spring 3 tends to force the bristles 5a of the brush 5 downwardly on the upper surface of the record A. As the record passes beneath the needle 1, the brush holder 4 pivots on the axis of the record A, whereby the bristles of the brush 5 are in trailing relationship with the point 1a of the needle 1, and substantially overlaps the path thereby, whereby adjacent spiral pathways of the needle in the record are cleaned prior to engagement of the needle point therewith. It will be noted that this brush 5 removes dust and other particles from the record such as record shavings and thereby reduces static pick-up in connection with the needle 1. Abrasive materials and other foreign matter are removed from the record by the brush 5, greatly prolonging the life of the record as well as the needle. Constant pressure of the bristles 5a on the upper surface of the record A maintained by the pressure of the spring 3 promotes automatic compensation for wear of the brush 5 and prolongs life of the same. The electrical insulation 4b of the brush holder 4, prevents transfer of static from the brush 5 to the needle 1. Thus, reception is greatly increased by removing static har-

boring dust and foreign matter from the upper surface of the record and preventing the transfer of said static from said brush to said needle. Intimate contact of the brush 5 being maintained constantly at all times by means of the compression spring 3 insures uniformity of operation and long life of the record, the needle and the brush. In assembling the brush in connection with the needle, the shank of the needle 1 is inserted through the bore portion 4c of the brush holder 4, then the spring 3 is placed over the shank of the needle 1 and then the clip 2 is placed in engagement with the annular groove 1b of the needle 1 so that the spring is maintained intermediate said clip 2 and said brush holder 4 on the needle 1.

Though I have shown and described a particular construction, combination and arrangement of parts and portions, I do not wish to be limited to this particular construction, combination, and arrangement, but desire to include in the scope of my invention the construction, combination and arrangement substantially as set forth in the appended claims.

Having thus described my invention, what I claim as new and desire to secure by Letters Patent is:

1. In a brush for phonograph needles of the class described, the combination of a needle having a point end, a brush holder freely pivoted on said needle axially thereof and having bristles in connection therewith extending in the same direction as said point end of said needle whereby movement of a record relatively to said needle causes said bristles to trail the point of said needle, and resilient means arranged to force said brush holder longitudinally of said needle toward the point end thereof.

2. In a brush for phonograph needles of the class described, the combination of a needle having a point end, a brush holder freely pivoted on said needle axially thereof and having bristles in connection therewith extending in the same direction as said point end of said needle whereby movement of a record relatively to said needle causes said bristles to trail the point of said needle, resilient means arranged to force said brush holder longitudinally of said needle toward the point end thereof, and electrical insulation in connection with said brush holder adjacent said needle.

3. In a brush for phonograph needles of the class described, the combination of a needle having a point end, a brush holder freely pivoted on said needle axially thereof and having bristles in connection therewith extending in the same direction as said point end of said needle where-

by movement of a record relatively to said needle causes said bristles to trail the point of said needle, resilient means arranged to force said brush holder longitudinally of said needle toward the point end thereof, electrical insulation in connection with said brush holder adjacent said needle, and a clip in connection with said needle for abutting said resilient means at its one end.

4. In a brush for phonograph needles of the class described, the combination of a conventional long life needle having a pointed end, a brush holder freely pivoted on said needle axially thereof near the pointed end thereof, bristles in connection with said brush holder adapted to brush a record traversed by said needle, and resilient means tending to force said brush holder toward the pointed end of said needle.

5. In a brush for phonograph needles of the class described, the combination of a conventional long life needle having a pointed end, a brush holder freely pivoted on said needle axially thereof near the pointed end thereof, bristles in connection with said brush holder adapted to brush a record traversed by said needle, resilient means tending to force said brush holder toward the pointed end of said needle, and insulation material in connection with said brush holder engaging said needle for preventing the conduction of static from said bristles of said brush to said needle.

6. In a brush for phonograph needles of the class described, the combination of a needle having a point end, a brush holder freely pivoted to said needle, brush bristles in said holder extending in the same direction as said point end of said needle; and resilient means for moving said bristles toward a phonograph record and relative to said needle, the brush trailing said needle.

WILLIAM H. ZIMMERMAN.
